UNITED STATES PATENT OFFICE

2,549,620

PUMPING MECHANISM

Orville Mitchell, Dallas, Tex., assignor to John E. Mitchell Company, Dallas, Tex., a corporation of Missouri

Application May 28, 1945, Serial No. 596,307

3 Claims. (Cl. 230—91)

1

The present invention relates to a pumping mechanism. More particularly, it relates to a liquid piston pumping mechanism and a system in which it is used.

It is an object of the invention to provide a liquid cylinder pumping system having multiple cylinders, one operating for pumping purposes while the other is on a suction stroke.

It is a particular object of the invention to provide a liquid piston pump having multiple pistons, one of which is on the compression stroke while the other is on the suction stroke, and both of which use the same body of liquid which is, under control, transferred from one cylinder to the other and back again. Hence, it is a further object of the invention to provide the control aforesaid for the transfer of the liquid forming the piston from one cylinder to the other, and, at the same time, to transfer control of the compression drum from one cylinder to the other.

It is a further object to provide the foregoing pumping system under control of a single motive means.

It is a further object to provide the foregoing with a single motor operating in a single direction, or with a reversible motor, as is desired.

It is a further object of the invention to provide a pump having very high volumetric efficiency, particularly through the elimination or reduction of waste space between the piston means and the exhaust valve. A further object is to provide increased valve efficiency, particularly by the reduction in the frequency of operation required of the control valves.

A further object is to provide increased heat efficiency and low cost of installation and construction.

In the drawings:

Fig. 1 is an elevation, partly in section, of a system as described;

Fig. 2 is a wiring diagram of the same;

Fig. 3 is a fragmentary view showing the use of a different type of pump; and

Fig. 4 is a wiring diagram for use with the modified type of pump.

This invention includes, in general, a liquid pump 10, a pair of liquid cylinders 11 and 12, a reversing valve and control 13, and a compressed air receiver 14, along with suitable piping connections for alternately conveying liquid and compressed air and finally forcing only compressed air into the receiver 14.

The pump 10 has an outlet 17, leading to a T 18. From the T 18, a branch 19 leads to an

2

automatic valve 20, such as a solenoid valve. From the valve 20, another line 21 leads to a T 22. From this T 22, a pipe 23 leads into the bottom of the so-called liquid cylinder, or container 11. From the T 22, there also leads a line 24 extending to another automatic solenoid valve 25, which is connected by a pipe 26 to a T 27. From the T 27, a line 28 is connected to the suction inlet of the pump 10. The foregoing forms one-half of the pipe network between the pump and the two liquid cylinders.

The connections for the liquid cylinder 12 are similar. From the T 18 connected with the pump outlet 17 another line 29 leads to a solenoid valve 30 that is connected by a pipe 31 to a T 32. From the T 32, a pipe 33 leads into the bottom of the liquid cylinder 12. Also, from the T 32, a pipe 34 leads to another automatic valve 35 that is connected by a pipe 36 with the inlet T 27.

A liquid supply 38, with a suitable valve, leads into the cylinder 11 to insure an adequate supply of liquid at all times.

The outlet sides of the two liquid cylinders 11 and 12 are likewise similar. The liquid cylinder 11 has an outlet pipe 40 that connects into a T 41. This T is connected with a suction line. To this end, it is connected directly to a suction check valve 42, into which an air supply line 43 leads. The other side of the T 41 is connected by a pipe 44 into a liquid chamber 45 of the control device 13. The chamber 45 is connected by a valve seat-containing port 46, with a cell 47 directly above the chamber 45. The chamber 47 has an outlet pipe 48 that leads to a check valve 49. The other side of the check valve is connected by a pipe 50 directly into the air receiver 14.

The chamber 45 receives a combination float and valve member 51 that is supported on a stem 52 that passes through the port 46. The stem 52 is attached to a flexible diaphragm 53 sealing off the top of the cell 47. The top end of the stem 52 is attached by a slot to one arm 54 of a bifurcated rocker arm member, generally designated at 55. This rocker arm is pivoted at 56 for its support.

The other liquid cylinder is connected by a pipe 60 into a T 61. This T is in similar manner connected through a suction check valve 62 with an air line 63. The other end of the T 61 is connected by a pipe 64 with a second chamber 65 within the control 13. The chamber 65 is connected through a valve seat-containing port 66 with a cell 67 directly above the chamber 65.

This cell is connected by a pipe 68 into a check valve 69, from which a pipe 70 leads into the air receiver 14.

The chamber 65 receives a combination float and valve 71 that is supported on a stem 72 that passes through the port 66. The stem is attached to a flexible diaphragm 73 that seals off the top of the cell 67. The top end of the stem 72 is attached by a slot to a second arm 74 of the rocker arm 55. The rocker arm 55 has a middle arm 77 to which one end of an over-center, snap-action spring 78 is secured. Its other end is attached in line below the pivot 66, to the valve casing.

The rocker arm 55 also operates a switch. To this end, the arm 54 carries a contact 81 that is adapted to make with a fixed contact 82. Likewise, the other arm 74 carries a contact 83 that is adapted to close with a fixed contact 84.

A typical wiring diagram is shown in Fig. 2, for use with a motor for a unidirectional pump, which will be assumed is in constant operation. Of course, it will be normally provided with a master switch control, or the like.

In Fig. 2, the power lines are shown at 86 and 87. The power line 86 is connected to the rocker arm 55, and thereby to the two contacts 81 and 83 thereof. Needless to say, the contacts are suitably insulated to prevent electrical grounding.

The contact 81 is adapted to close with the contact 82, which latter is connected by an electrical lead 88 to a terminal 89. The terminal 89 is connected by a line 90 to the coil of the valve 20, the other end of which is connected by a line 91 to a terminal 92. The terminal 92 is connected by a line 93 to a terminal 94.

The terminal 89 is also connected by a line 95 through the coil of the valve 35, from whence it is connected by a line 96 to a terminal 97. The terminal 97 is connected by a line 98 to the terminal 84, which is connected to the other power line 87.

The contact 83 of the rocker arm 55 is adapted to close with a fixed contact 84. This latter is connected by a line 99 to a terminal 100. The terminal 100 is connected by a line 101 into the coil of the valve 25, from which it is connected by a coil 102 to the terminal 92.

Another line 104 leads from the terminal 100 into the coil of the valve 25, from which a line 105 leads to the terminal 97.

In Fig. 3, a reversible motor is used operating a reversible pump. The reversible motor is shown at 115 and is connected by a belt to the reversible pump 116. This pump is connected by a line 117 into the liquid cylinder 11, and by a line 118 into the cylinder 12. The connections for this compressor are shown in Fig. 4. The rocker arm 55, in this case, is actuated by the same control mechanism 13. However, the contact 82 is connected by a line 120 into the forward windings of the motor 115, and the contact 84 is connected by a line 121 into the reverse windings of the motor. The lead 87 is also connected as a common into the motor.

Operation

An amount of operating liquid, such as water, is introduced through the inlet line 38 into the two liquid cylinders 11 and 12. The preferable amount will be somewhat more than enough to fill one of the two cylinders, as will appear.

In Fig. 1, the motor for the pump 10 is operating to pump through the left cylinder 11 and to apply suction through the other cylinder 12. It

has almost finished its stroke. The motor of the pump 10 is operating. It will also be seen that the rocker arm 55 is in position to close the two contacts 81 and 82 and to maintain the contacts

- 5 23 and 84 open. Thus power is introduced from the power line 86 through the contact 82, the line 88, to the junction 89, from whence it divides, by the line 90 through the valve 20, the line 91, the junction 92, the line 93 and the junction 94 to 10 the other power line 87. At the division point 89, it also is connected through the line 95, the valve 35, the junction 97, and the line 98, to the junction 94 and the other power line 87. By this means, the two valves 20 and 35 are opened. 15 When these two valves are opened, and the other two valves 30 and 25 are deenergized and hence closed, the suction line 28 of the pump 10 will be connected to the right hand liquid cylinder 12 through the pipe 33, the T 32, the pipe 34, the valve 35, the pipe 36 and the T 21. The pipe 34 will be blocked off by the closed valve 30 and the pipe 26 will be blocked off by the closed valve 25. The high pressure outlet line of the pump 10 will be connected by the pipe 17 to the T 18, and thence through the pipe 19 and the open valve 20, the pipe 21, the T 22, and the pipe 23 25 into the pressure liquid cylinder 11. The closure of the valves 25 and 30 prevents backflow or parasitic flow through both the pressure and the 30 suction lines.

The water will then be forced upwardly into the cylinder 11 and suction will be applied to the cylinder 12 as the water is drawn therefrom. The suction draws air in from the inlet 63 through 35 the check valve 62 to the T 61, and thence by the pipe 60 into the cylinder 12. At this time, and in the position shown, the liquid cylinder 11 has been filled and the water has been forced out through the pipe 40 and the T 41. The check 40 valve 42 prevents passage of this water back into the air inlet line 43, so that it is forced out through the pipe 44 into the chamber 45 of the control 13.

After a relatively small additional quantity of 45 water, beyond that shown in Fig. 1, is forced into the chamber 45, it will float the float 51, which will be moved upwardly in the chamber. This upward movement will rock the rocker arm 55 and will finally throw the spring 78 over center, which will lower the float 71 and will quickly draw the float 51 up into the valve seat 46, sealing flow therefrom. It is, of course, understood that the float 71 at the same time opens the valve seat 66.

55 The upward movement of the liquid in the liquid cylinder 11 and finally in the chamber 13 forces air above the liquid column out past the float 51, through the port 46 and out into the cell 47, out the line 48, past the check valve 49, and 60 by the pipe 50 into the receiver 14. This flow is obstructed when the rocker arm 55 shifts over as aforesaid to close the float 51 into the seat 46 and to open the float 71 in the seat 66.

When the rocker arm 55 thus shifts over center, closing the float valve 51 and opening the float valve 71, it also shifts the circuits, as shown 65 in Fig. 2. It opens the contacts 81 and 82, thereby breaking the circuits to the valve coils 20 and 35, so that these two valves close. At the same time, however, it closes the contacts 83 and 84. When these two contacts are thus closed, the power from the line 86 flows through them and thence, by way of the line 99, to the junction 100. From the latter, it flows through the line 101 70 through the coil of the valve 25, and by the line 75 through the coil of the valve 30, and by the line

102 to the junction 92, thence by the line 93 to the junction 94 and the other power line 87. It also flows from the previously mentioned junction 100 through the line 104 to the coil of the valve 25, and thence by way of the line 105 to the junction 97, and by the line 98 to the junction 94 in the other power line.

As a result of this shift of the rocker arm 55, the two valves 20 and 35 are released to closed position as aforesaid, but the two valves 30 and 25 are opened. This reverses the flow of the water although the pump continues to run in the same direction. The pump inlet 28 is now connected to draw water from the liquid cylinder 11 through the pipe 23, the T 22, the pipe 24, the open valve 25, and the pipe 26. The closure of the valve 35 cuts the other liquid cylinder 12 from this suction line, and, of course, the parasitic suction line is cut off by the closure of the valve 20. The high pressure line 17 from the pump 10 is now connected through the valve 30 and the pipe 31 to the T 32 and the pipe 33, to discharge water into the liquid cylinder 12. The closure of the valve 20 prevents the flow of this water into the cylinder 11.

The foregoing disposition of the network thereby effects a withdrawal of the water from the cylinder 11 and its pressure discharge into the liquid cylinder 12. As the level rises within the liquid cylinder 12, the air that was drawn in during the previous suction stroke is now forced up through the pipe 60, the T 61, the pipe 64, the chamber 65, past the port 66, into the cell 67, and thence past the check valve 69 and into the receiver 14. Likewise, the lowering of the level of the water within the liquid cylinder 11 draws in additional air through the air line 43, past the check valve 42, and by the pipe 40 into the cylinder. At this time, the closure of the check valve 49 within the line 50 and the closure of the float valve 51 prevents suction of air from the receiver 14.

When the modification of Figs. 3 and 4 is used, with a reversible motor, it is not necessary to have the pipe network shown in Fig. 1. It is necessary only to have a line from the pump to each of the two liquid cylinders 11 and 12, these two lines being shown at 117 and 118 in Fig. 3. The control 13 is the same as before. However, when the float is in the position shown in Figs. 1 and 4, closing the contacts 81 and 82, the power is introduced from the line 86 through the contacts 81 and 82, and by the line 128 to the forward winding of the motor 115, and thence to the other power line 87. This drives the motor in its forward direction and will pump the liquid into the cylinder 11 by way of the pipe 117, at the same time drawing the liquid from the liquid cylinder 12 through the pipe 118. When the control 13 shifts, it opens the contacts 81 and 82, de-energizing the forward windings of the motor 115, and it closes the contacts 83 and 84 to energize the reverse winding of this motor. This latter circuit passes from the power line 86 through the contacts 83 and 84, the line 121, to the motor 115, and thence to the power line 87. This reversal changes the direction of the water flow within the system, withdrawing water from the cylinder 11 through the pipe 117, and discharging it under pressure through the pipe 118 into the liquid cylinder 12.

By the foregoing means, it will be seen that air is at all times being compressed into the receiver 14, from one or the other of the two liquid cylinders 11 and 12. The liquid pump of this type has

the advantage of great heat efficiency, as the heat generated by the compression of the air may flow into the water and be dissipated thereby. Great volumetric efficiency can be obtained because the piston, being liquid, can flow right up against the valves, and no mechanical clearance is required at the end of the piston strokes to accommodate the valve operation. Where the average air compressor operates with a volumetric efficiency of about seventy percent, the present pump can attain as high as ninety-nine percent volumetric efficiency. The latter, in the present system, is controlled by the ratio of the size of the liquid cylinder and the clearance between the water piston and the valve.

The frequency of operation of the valves in the liquid system here presented is very much less than that required of a mechanical type of pump. This fact, along with other factors that will be obvious, reduces the wear on the valves very substantially.

Furthermore, there is a great reduction in cost in the liquid pump system. All of the equipment used herein consists of a simple pump with plain tanks, simple valves, and ordinary piping, with a reversing control that is free of complications. It is inexpensive to operate and simple to install.

What is claimed is:

1. In a gas compressing system of the liquid piston type, a pair of relatively large liquid containers, a pair of relatively small float chambers, one connected with the top of each liquid container, a gas outlet from the top of each float chamber, the float chambers being thereby connected in series with their respective liquid containers, valve means adjacent the float chambers permitting gas flow only outwardly from the chambers through the gas outlets, a unidirectional gas inflow conduit for admitting gas into each liquid container, a float device in each chamber, means to transfer a quantity of liquid alternately from one liquid container and its float chamber, to the other liquid container and its float chamber, such liquid rising in each float chamber until it lifts the float device therein, means responsive to elevation of each float device to reverse the travel of the liquid, and cause it to be withdrawn from such float chamber and liquid container until it fills the other liquid container and float chamber, there being means to maintain the float device so elevated, in elevated position until the liquid rises in the other float chamber and elevates the other float device therein.
2. In a gas compressing system of the liquid piston type, a pair of relatively large liquid containers, a pair of relatively small float chambers, one connected with the top of each liquid container, a gas outlet from the top of each float chamber, the float chambers being thereby connected in series with their respective liquid containers, valve means permitting gas flow only outwardly from the chambers through the gas outlets, a unidirectional gas inflow conduit for admitting gas into each liquid container, a float device in each chamber, means to transfer a quantity of liquid alternately from one liquid container and its float chamber, to the other liquid container and its float chamber, such liquid rising in each float chamber until it lifts the float device therein, means responsive to elevation of each float device to reverse the travel of the liquid, and cause it to be withdrawn from such float chamber and liquid container until it fills the other liquid container and float chamber,

there being means to maintain the float device so elevated, in elevated position until the liquid rises in the other float chamber and elevates the other float device therein, the unidirectional gas inflow conduits being connected into the system between the maximum liquid level in the float chambers, and the tops of the liquid containers.

3. In a gas compressing system of the liquid piston type, a pair of relatively large liquid containers, a pair of relatively small float chambers, one connected with the top of each liquid container, a gas outlet from the top of each float chamber, the float chambers being thereby connected in series with their respective liquid containers, valve means permitting gas flow only outwardly from the chambers through the gas outlets, a unidirectional gas inflow conduit for admitting gas into each liquid container, a float device in each chamber, means to transfer a quantity of liquid alternately from one liquid container and its float chamber, to the other liquid container and its float chamber, such liquid rising in each float chamber until it lifts the float device therein, means responsive to elevation of each float device to reverse the travel

of the liquid, and cause it to be withdrawn from such float chamber and liquid container until it fills the other liquid container and float chamber, there being means to maintain the float device so elevated, in elevated position until the liquid rises in the other float chamber and elevates the other float device therein, each float device having a valve portion, and a valve seat in the outlet from each float chamber, that is closed by said valve portion when the float is elevated as aforesaid.

ORVILLE MITCHELL.
